UNITED STATES PATENT OFFICE.

ROBERT P. STEPHENS, OF RATON, NEW MEXICO.

CHANGEABLE EXHIBITOR.

1,150,814.

Specification of Letters Patent. Patented Aug. 17, 1915.

Application filed April 25, 1914. Serial No. 884,448.

To all whom it may concern:

Be it known that I, ROBERT P. STEPHENS, a citizen of the United States, residing at Raton, in the county of Colfax and State of New Mexico, have invented new and useful Improvements in Changeable Exhibitors, of which the following is a specification.

This invention relates to improvements in changeable exhibitors, such as calendars and like exhibitors of that type employing a moving web, one object of the invention being to provide simple and effective means for securing an observation panel in position, said securing means forming part of a means for guiding the moving web in determined relationship to the panel.

A further object of the invention is to provide securing and guiding means of the character set forth which are integral with the material of the casing.

A still further object of the invention is to provide a novel construction of calendar casing, and means for attaching the same to a bracket or other supporting means.

The invention consists of the features of construction, combination and arrangement of parts herein fully described and claimed, reference being had to the accompanying drawings in which:

Fig. 1 is a perspective view of a calendar embodying my invention, as adapted for use as a desk calendar. Fig. 2 is a vertical front to rear section through the same. Fig. 3 is a vertical longitudinal section. Figs. 4 and 5 are horizontal transverse sections taken, respectively, on the lines 4—4 and 5—5 of Fig. 3. Fig. 6 is a detail view of the bracket plate, showing a feature of construction. Fig. 7 is a detail view showing another feature of construction.

Referring to the drawing, 1 designates an inclosing box or casing, preferably of rectangular form and bent from a blank of sheet metal, the said casing comprising a front wall 2, side walls 3, a bottom wall 4 and a top wall 5, and being open at the rear, as shown. The front wall of the casing is provided with a display opening 6 to expose the moving calendar web 7, and, as shown, this opening is preferably closed by a transparent panel 8, of glass or equivalent material, fitted at its edges in receiving grooves 9 formed by flanges 10 bent inwardly from the upper and lower walls of the opening, the inner webs of the flanges providing clips to engage and clamp the upper and lower

edges of the glass panel in position. At the side walls of the opening the metal of the casing is also bent inwardly to provide flanges 10, having longitudinal guide slots 10^a, portions of the metal of which said flanges are composed being bent laterally to form clips or clamping members 10^b engaging and holding the side edges of the glass panel 8 in position. The slots 10^a form guides through which the portion of the web 7 which is to be displayed travels, whereby such portion of the web is held in position parallel with the panel. Disposed within the casing on opposite sides of its center are rolls or spools 11 and 12, each having end disks or heads 13. The web is wound in the form of a roll upon the spool 11 and is adapted to wind therefrom to the spool 12, so that the portions thereof carrying the calendar matter may be successively displayed at the opening 6. The spools are detachably mounted in position, each having at its lower end a bearing recess 14 to receive a bearing stud 15, said studs being carried by spring plates 16, struck up from the bottom wall 4. The upper ends of the spools 11 and 12 are formed with angular sockets 17 to respectively receive angular projections 17' upon the stub shafts or spindles 18 and 19 journaled upon the top wall 5, which shafts or spindles are provided with gears 20 and 21 meshing with an intermediate operating gear 22 carried by a spindle 23, also journaled upon the top wall, and provided with a winding key or finger piece 24. By turning this key motion may be simultaneously transmitted to the spools to unwind the web from one spool and wind the same upon the other spool, enabling the web to be easily and conveniently adjusted as occasion requires. A spring strip 25 is struck up from a bracket or back plate 26 and acts upon the gear 22 as a friction brake to prevent casual movement of the spools and shifting of the web.

It will be understood from the foregoing description that the spools are mounted for rotation upon the bearing studs 15 and with the spindles 18 and 19, to which they are detachably coupled by the sockets 17 and recesses 17', said parts being held in coupling engagement by the upward spring pressure of the members 16, and it will also be understood that by pressing downward upon the spools or downward upon the members 16 the latter will yield, allowing the

upper ends of the spools to be disengaged from the projections 17' and the spools to be released and removed. By this construction the application and removal of the spools in a ready and convenient manner is insured, so that new webs may be applied when occasion requires. If desired, also, the web may bear upon its opposite faces calendar matter for different years or periods, so that after one face thereof has been exposed the spools may be removed and reversed so as to dispose the opposite face of the web for use, thus providing a calendar of economical construction which may be employed for a long period.

The bracket or backing plate 26 may be made of sheet metal or other suitable material and is provided to close the rear wall of the casing 1, as well as to serve as a support to hold the calendar upright upon a desk or other base. This backing or bracket plate is cut away at its lower end to provide supporting legs 27 and at its rear is provided with a detachable brace 28 to hold it at a desired angle of inclination. The brace is preferably formed of sheet metal and is provided at its front edge with laterally bent flanges 29 engaging a slot 30 formed in the plate, whereby the brace and plate are detachably coupled. In the plate are provided openings 31 for the passage of tongues 32 on the casing, by which the latter is detachably secured thereto, allowing the casing to be removed whenever it is desired to replenish or reverse the spools.

It will, of course, be understood that the structure as a whole may be made as cheaply or as ornamental as desired, and that the face of the backing plate may be devoted to advertising purposes.

I claim:-

1. In a changeable exhibitor, a casing

formed of sheet metal having an observation opening in the front wall thereof, flanges integral with the casing at the sides of said opening and extending inwardly at right angles from said front wall and provided with guide slots, portions of the metal from which said slotted flanges are formed being bent parallel with the front wall to provide clips, and a transparent panel having its side edges engaged and clamped against the front wall by said clips, whereby a web may be arranged to travel through said guide slots and in a determined relationship to the rear surface of the transparent panel.

2. In a changeable exhibitor, a casing formed of sheet metal having an observation opening in the front wall thereof, flanges integral with the casing at the top and bottom of the opening and folded upon themselves to form grooved receiving and holding members, flanges integral with the casing at the sides of said opening and extending inwardly at right angles from said front wall and provided with guide slots, portions of the metal from which the said slotted flanges are formed being bent parallel with the front wall to provide clips, and a transparent panel having its upper and lower edges fitted in and held by said grooved retaining members and its side edges engaged and clamped against the front wall by said clips, whereby a web may be arranged to travel through said guide slots and in a determined relationship to the rear surface of the transparent panel.

In testimony whereof I affix my signature in presence of two witnesses.

ROBERT P. STEPHENS.
